UNITED STATES PATENT OFFICE.

THEODORE LINKE, OF NEW YORK, N. Y.

FILTER.

SPECIFICATION forming part of Letters Patent No. 789,617, dated May 9, 1905.

Application filed May 28, 1903. Serial No. 159,105.

To all whom it may concern:

Be it known that I, THEODORE LINKE, a citizen of the United States, and a resident of the city of New York, borough of Manhattan, in 5 the county and State of New York, have invented a new and Improved Filter, of which the following is a full, clear, and exact description.

This invention relates to improvements in 10 filtering-faucets, the object being to provide a filtering-faucet of simple construction so arranged that either filtered or unfiltered water may be discharged from it, that may be conveniently manipulated by a handle at the 15 top, that may be readily dismembered for repairing without discharging water, and which has a novel arrangement of stone-cleaners.

I will describe a filter embodying my invention and then point out the novel features in 20 the appended claim.

Reference is to be had to the accompanying drawings, forming a part of this specification, in which similar characters of reference indicate corresponding parts in both the figures.

25 Figure 1 is a sectional elevation of a filter embodying my invention, and Fig. 2 is a section on the line 2 2 of Fig. 1.

The body of the filter consists of a cylinder 1, preferably of glass, so that the interior working of the device may be readily observed. This cylinder is secured between a metal top plate 2 and a metal bottom plate 3. The said plates are of somewhat larger diameter than the cylinder, and passing through the plates 30 at the outer side of the cylinder are the clamping-bolts 4. On the upper plate 2 is a tubular projection 5, the opening in the upper portion of which is somewhat reduced in diameter and is interiorly threaded to receive the thread 40 on a rod 6, provided with a handle 7. The water is discharged into the enlarged portion of the extension 5 through a pipe 8.

On the inner end of the rod 6 is a plate 9, having a packing 10 on its upper face designed 45 to engage with a valve-seat 11, surrounding the lower portion of the opening in the extension 5, and removably engaging with the inner end of this rod 6 is a rod 12, having wings 13 extended lengthwise of it. Attached 50 to the lower end of this rod 12 is a plate 14,

from which a discharge-tube 15 for filtered water extends downward, and extended downward from said plate 14 and surrounding the tube 15 is a tube 16, through which unfiltered water may be discharged, this tube 16 being 55 provided near the plate 14 with ports 17. The tube 16 is movable in a tubular projection 18 on the plate 3. A cylindrical filtering-stone 19 surrounds the rod 12 and is clamped between the plates 10 and 14. To make a tight 60 connection between the plates and stone, rubber washers 20 21 are placed between the plates and stone. The wings 13 bear against the inner surface of the stone; but the space between the wings permits the water to pass 65 down through ports 22 into the tube 15. As the rod 12 has screw-thread connection with the rod 6, it is obvious that the parts may be separated to remove the stone when necessary or to place a new stone in position. 70

Bearing upon the stone are scraping or cleaning devices, consisting of spring-yielding plates 23, and, as here shown, these plates are connected to posts 24, extended upward from the lower plate 3. For convenience in attaching the plates to the posts the said posts may be longitudinally slotted and the plates slid therein. The width of each plate extended circumferentially of the stone approximates one-fourth the stone's circumference, thus providing sufficient yielding movement in comparatively thick plates not liable to break or fracture. 75

In the operation when the parts are in the position indicated in Fig. 1—that is, with the 80 valve 10 out of engagement with the seat 11 and the ports 17 above the plate 3—unfiltered water may flow out through the tube 16. When it is desired to filter the water before discharging, the rod 6 is to be turned, thus 85 forcing the stone downward, and consequently moving the ports 17 into the tubular projection 18 or into the rubber washer 26, supported at the upper end of said projection. The water will then filter through the stone 90 and pass out through the tube 15. When it is desired to entirely cut off the water, the rod 6 is to be turned to engage the valve 10 with the seat 11. It will be noted that during 95 the rotary motion of the stone the scraping 100

or cleaning devices will be brought into operation to clean off any scum that may have accumulated on the outer surface of the stone. As the water enters the top it may be readily 5 shut off at the top of the filtering device, so that the parts may be dismembered by removing the nuts from the bolts 4, whereupon the lower plate and the glass cylinder move downward, carrying with them the cleaning 10 devices, and then by detaching the rod 12 from the rod 6 the stone may be removed.

By the construction of my device as described only one valve-operating rod is required to adjust the parts, permitting unfiltered water to pass through to adjust the 15 parts for discharging filtered water and for entirely cutting off the inlet of water when it is necessary to separate the several members, and by placing the handle at the top 20 the manipulation of the valve-rod is much handier than when placed at the lower end of the filter.

Having thus described my invention, I claim as new and desire to secure by Letters Patent— 25 A filter comprising a body portion, top and

bottom plates between which the body portion is clamped, a tubular upward extension on the top plate forming an inlet for water, a valve-seat surrounding the inner end of said tubular extension, a screw-rod operating in 30 said extension, a valve carried by the inner end of said rod for engaging said valve-seat, a winged rod having screw-thread engagement with the first-named rod, a plate on the lower end of said winged rod, a tube extended 35 downward from said plate, a perforated tube extended from the plate and surrounding the first-named tube, a tubular projection on the lower plate, a packing arranged in the said lower plate for closing the perforations of the 40 second-named tube, and a tubular filter-stone surrounding the winged rod and clamped between said plates.

In testimony whereof I have signed my name to this specification in the presence of two sub- 45 scribing witnesses.

THEODORE LINKE.
